UNITED STATES PATENT OFFICE.

JOHN AUGUSTUS HICKS, OF SUMMIT, NEW JERSEY, ASSIGNOR TO JAMES M. HICKS, OF SUMMIT, NEW JERSEY.

CAP-FEEDING MACHINE.

No. 845,415.

Specification of Letters Patent.

Patented Feb. 26, 1907.

Application filed March 31, 1905. Serial No. 253,069.

To all whom it may concern:

Be it known that I, JOHN AUGUSTUS HICKS, a citizen of the United States, county of Union, State of New Jersey, residing at Summit, in said county and State, have invented certain new and useful Improvements in Cap-Feeding Machines, of which the following is a specification.

My invention relates to machines for automatically delivering metal caps from a mass to a capping-machine one at a time successively; and to this end it consists in certain elements and combinations fully set out and claimed at the end of the following specification.

In order that persons skilled in the art to which my invention appertains may understand, construct, and use my invention, I will proceed to describe it, referring to the accompanying drawings, forming part of this specification, in which—

Figure 1 is a side elevation of my invention attached to and above my capping-machine, which capping-machine is fully illustrated and specified in an application filed in United States Patent Office March 31, 1905, Serial No. 253,155. Fig. 2 is a top view of the said capping-machine with the ratchet mechanism attached for driving the feeding mechanism located above it. Fig. 3 is a top view of the hopper for holding a mass of caps and also the cone, carrier, and appliances for delivering one cap at a time to a chute which leads from said hopper to the capping-machine. Fig. 4 is a sectional view of the said hopper and chute, the cone, carrier, and other appliances being shown in side view. Fig. 5 is a top view of a portion of the cap-transferring chute, in which the caps are turned to a uniform position bottom up previous to entering the portion of said transferring-chute which reverses their position, turning them top up before reaching the capping-machine, delivering them at a definite point in the pocket-wheel. Figs. 8, 7, 6, respectively, are cross-sectional views, respectively, on lines X X, Y Y, Z Z, Fig. 5.

A is the hopper.

B is the cone-carrier.

C is a chute attached to the bottom plate of hopper A and opening into it.

D is a vertical shaft which passes up through the center of the cone-carrier B and at its top enters a cross-brace E to center it, which

cross-brace E is fastened to the sides of hopper A.

F is one part of a universal joint on the lower end of shaft D, and F' is the other half on the upper end of a shaft D'. F² and F³ are a universal joint at the lower end of shaft D', and is secured on the upper end of shaft D², which takes onto a pin on which ratchet G is centered and revolves step by step by mechanism which works the capping-machine. The ratchet G is supported upon a bracket G', fastened to the top plate E' of the capping-machine. Thus the cone-carrier B is moved circumferentially step by step by rods D D' D² in operative connection with ratchet G, operated in unison with mechanism which operates the capping-machine to which it is attached and which is to receive the caps one by one in a pocket-wheel arranged therefor at the base of chute C and its lower connections.

Around the vertical periphery of carrier-cone B, which is smaller than the inside of hopper A, are lugs B', which divide the space between cone B and hopper A into pockets B², into which caps from hopper A drop and are carried around until they reach, one at a time, the opening A, above the chute C, into which chute C they drop and roll down said chute to the part C² indiscriminately, the caps being turned part one way and part the other. The carrier-cone B has wings B³, which agitate the mass of caps in hopper A. Incline strips B⁴ are secured to the inner surface of hopper A, running circumferentially, starting at a point or points about the level with the top of lugs B' and rise considerably above said level at their extreme ends. The wings B³ on the revolving carrier B move the caps which may be above the pockets between the lugs B' around and roll them up the incline strips B⁴ and over their extreme ends, so that in case two caps have become cupped one inside the other as they drop over the ends of the incline pieces B⁴ they are reversed and uncupped. The sides of chute C², from a definite point downward to the opening in chute C³, are inclined outward gradually, and the bottom plate to chute C² is raised at the central portion from a definite point in chute C' (C' from where it joins the part C has its sides vertical, as shown in Figs. 6, 7, and 8, the incline sides beginning at C²) and downward to near the mouth of chute C³, so that

caps rolling down chute C' on reaching chute C² are inclined against whichever side the weight of the heaviest portion of the cap inclines them, which is the top side, the raised center aiding this operation, so that when the inclined caps reach about the mouth of chute C³ the caps are turned top down to pass on through chute C³, and, as chute C³ is curved over, the caps in passing through chute C³ are turned in position from bottom up to top up and in condition to pass into a pocket in pocket-wheel E² in the capping-machine, to which the chute C³ is attached, and into whichever pocket may be opposite the opening in chute C³.

The operation of my invention is as follows: A mass of caps is placed in hopper A, caps fall into pockets B² of the cone-carrier, the capping-machine is worked by its step-by-step mechanism, as shown in my application for capping-machine above referred to, and the rod D' is turned, bringing one of the pockets B² over the entrance to chute C, and a cap drops into the said chute and rolls down chute C' to chute C² and is there turned upon its top side, no matter how the cap is faced in leaving the hopper A and pocket B². As the cap leaves chute C², lying upon its top side, the chute C³ being curved changes the lay of the cap to bottom side down and in condition to enter a pocket-wheel E² in the capping-machine and as it should be to be placed over a vessel mouth. The same operation takes place for every movement of the cone-carrier forward one pocket one step at a time, controlled and timed by the ratchet mechanism which drives the cone-carrier B from the capping-machine and in unison with it. In case the caps lock into each other, and thus are hindered from dropping into the pockets B², the wings B³, by the revolution of cone-carrier B, roll the locked caps up the incline B⁴ and drop them over the ends of the inclines, and thus they become uncapped.

Having now fully described my invention and the manner in which I have embodied it, what I claim as new and as my invention, and desire to secure by Letters Patent, is—

1. In a machine for delivering sealing-caps to a capping-machine one at a time, the combination consisting of a circular hopper to hold a mass of caps; a circular carrier located

within said hopper pivoted to revolve therein centrally and provided with equally-spaced pockets on its periphery and embraced between the internal circumference of said hopper and said carrier; an opening in the base of said hopper and under a pocket in the said carrier; a chute located beneath said opening to receive caps as they drop into it through said opening; a rectifying-chute connected therewith for facing the caps alike; a reversing-chute as a continuation of said rectifying-chute to convey caps properly faced to a capping-machine; step-by-step mechanism, consisting of a ratchet mechanism, and driving connections therefrom to the pivotal shaft for driving the said carrier, whereby caps are delivered from the said hopper one by one, to a capping-machine properly faced for the said capping-machine, substantially as specified.

2. In an apparatus for holding a mass of caps and delivering one cap at a time to a rectifying-chute, the combination consisting of a circular hopper; a carrier centrally and pivotally located in said hopper and of substantially smaller inner diameter than the diameter of the said hopper, division-pieces secured to the outer diameter of the said carrier to form equal pockets bounded by the carrier, the inside diameter of the hopper and the said division-pieces; an opening in the base of said hopper and beneath one of the said pockets in and above the said chute; upwardly-inclined pieces located on the inner surface of the said hopper; wings projecting from the outer surface of the carrier; a pivotal shaft secured to the said carrier and journaled in the center of the base of said hopper and connected with the operating mechanism of a capping-machine, whereby the said carrier is operated circumferentially step by step, as and for the purposes hereinbefore specified.

In testimony whereof I have signed my name to this specification, in the presence of two subscribing witnesses, this 30th day of March, 1905.

JOHN AUGUSTUS HICKS.
